UNITED STATES PATENT OFFICE.

LUCY DUFF-GORDON, OF NEW YORK, N. Y.

DESIGN FOR AN AVIATION COSTUME.

51,057.

Specification for Design.

Patented July 24, 1917.

Application filed March 31, 1917. Serial No. 159,043. Term of patent 3½ years.

To all whom it may concern:

Be it known that I, LUCY DUFF-GORDON, a subject of the King of Great Britain, and a resident of the city of New York, borough of Manhattan, in the county and State of New York, have invented a new, original, and ornamental Design for an Aviation Costume, of which the following is a specification, reference being had to the accompanying drawings, forming a part thereof.

I claim:

The ornamental design for an aviation costume as shown.

LUCY DUFF-GORDON.
